UNITED STATES PATENT OFFICE.

HERMANN H. FISCHER, OF OSAGE, NEBRASKA.

HARROW-EVENER.

SPECIFICATION forming part of Letters Patent No. 252,751, dated January 24, 1882.

Application filed November 11, 1881. (Model.)

To all whom it may concern:

Be it known that I, HERMANN H. FISCHER, of Osage, Otoe county, Nebraska, have invented a new and useful Improvement in Harrow-Evener, of which the following is a specification.

Reference is to be had to the accompanying drawings, in which similar letters of reference indicate corresponding parts in all the figures.

10 Figure 1 is a perspective view of my improvement, shown as applied to a harrow. Fig. 2 is a plan view of the evener, and Fig. 3 is a rear elevation of the same.

15 The object of this invention is to promote convenience in clearing harrows of collected rubbish, and in adjusting them to harrow the ground fine or coarse.

20 The invention consists in a harrow-evener constructed of two triangular frames hinged to each other by a rod; also, in the combination, with the harrow-frame and the double-tree, of two triangular frames and their hinging-rod, whereby either part of the harrow-frame can be raised from its rear end or outer side to discharge collected rubbish without affecting the other part; and, also, in the combination, with the straight bars of the hinged triangular frames, of a stop-plate attached to the bar of the one frame and overlapping the underside of the 25 bar of the other frame, whereby the outer ends of the hinged frames are kept from dropping too low, as will be hereinafter fully described.

25 A represents a bar, to which, near its outer end, is attached the outer end of a bar, B. The bars A B incline from each other, and are connected at a little distance from their inner ends by a short bar, C, the ends of which are secured to the said bars A B by bolts or rivets. By 30 this construction a triangular frame is produced, and two of these frames form my improved evener.

35 The two frames A B C are hinged to each other by a rod or long bolt, D, which passes through perforated lugs formed upon the ends 40 of the bars A B, the relative lengths of the said bars A B being such that the rod D will be at about right angles with the bars A. To the lower side of one of the bars A is attached a

plate, E, which overlaps the under side of the other bar A, as shown in Figs. 1, 2, and 3, to 50 prevent the outer ends of the said frames A B C from swinging too far downward.

The two bars A are connected with the harrow-frames F by clevises G in the ordinary manner, and several sets of holes are formed in 55 the said bars to receive the clevis-pins, so that the same evener can be applied to different-sized harrow-frames, as may be required.

The draft is applied to one or the other of the bars B, and several holes are formed in the 60 said bars to receive the double-tree clevis-pin, so that the point of draft attachment can be changed to cause the tracks of the harrow-teeth to be closed together or farther apart, according as it is desired to harrow the ground finer 65 or coarser.

The double-tree H, the whiffletrees I, and the double-tree clevises J are made in the ordinary manner.

With this construction either part of the harrow can be raised to discharge the collected rubbish without affecting the position of the other part, and either part can be raised from its rear end and its outer side with equal facility.

Having thus described my invention, I claim as new and desire to secure by Letters Patent—

1. The herein-described harrow-evener, consisting of two triangular frames hinged together at their bases, as set forth.

2. In a harrow-evener, the combination, with the harrow-frame F and the double-tree H, of the two triangular frames A B C and the hinging-rod D, substantially as herein shown and described, as set forth.

3. An improved harrow-evener, consisting of the triangular frames A B C, hinged together at their bases and provided with the plate E, secured to the under side of one of the bars A, with its end projecting beyond said bar under 90 the end of the other bar, substantially as and for the purpose set forth.

HERMANN HEINRICH FISCHER.
